UNITED STATES PATENT OFFICE.

SAMUEL T. NEWMAN, OF DANBURY, AND EDWIN C. OAKLEY, OF BETHEL,
ASSIGNORS, BY DIRECT AND MESNE ASSIGNMENTS, TO HENRY GRIFFIN
AND CHARLES H. MERRITT, BOTH OF DANBURY, CONNECTICUT.

HAT-POUNCING MACHINE.

SPECIFICATION forming part of Letters Patent No. 447,787, dated March 10, 1891.

Application filed May 29, 1889. Serial No. 312,539. (No model.)

To all whom it may concern:

Be it known that we, SAMUEL T. NEWMAN, of Danbury, in the county of Fairfield and State of Connecticut, and EDWIN C. OAKLEY, 5 of Bethel, in the said county and State, have invented a certain new and useful Improvement in Hat-Pouncing Machines, of which the following is a specification.

The object of our improvement is to produce 10 a machine which will perform that pouncing that is usually done by hand in finishing the crowns of hats.

We will describe a machine embodying our improvement, and then point out the novel 15 features in the claims.

In the accompanying drawings, Figure 1 is a side view of a machine embodying our improvement. Fig. 2 is a view of the other side of the machine. Fig. 3 is a plan or top view. 20 Fig. 4 is an end view. Fig. 5 is an end view of the machine, looking from the opposite direction, certain parts being omitted. Fig. 6 is a vertical transverse section taken at the plane of the dotted line $x\ x$, Fig. 1, and looking 25 in the direction indicated by the arrow at the end of this line. Fig. 7 is a horizontal section taken at the plane of the dotted line $y\ y$, Fig. 1, and looking upwardly, as indicated by the arrow at the end of this line. Fig. 8 is a sectional view of a pouncing-pad and certain parts with which it is combined. Fig. 9 30 is a side view of the pad as seen from a plane at right angles to that of Fig. 8. Fig. 10 is a sectional side view of a reversible pad. Fig. 85 11 is a view of a pad and the parts which support it. Fig. 12 is a view of another pad and the parts which support it. Figs. 11 and 12 are views taken from the side of the machine which is represented in Fig. 1.

40 Similar letters of reference designate corresponding parts in all the figures.

A designates the bed-piece of the machine. It may be made of metal or other suitable material and secured to a table or any other 45 suitable support.

B designates the driving-shaft of the machine. It is provided with a fast pulley b' and a loose pulley b'' for receiving a belt used to transmit motion to the shaft. This belt 50 may be shifted from the fast pulley to the

loose pulley when the motion of the shaft is to be stopped, and from the loose pulley to the fast pulley when the shaft is desired to be rotated, by means of a belt-shifter of any desired kind.

We have shown a belt-shifter consisting of an arm C, provided with pins c, and affixed to a rock-shaft C', supported in a portion a' of a frame A', that is bolted or otherwise secured to the base-piece. The rock-shaft C' has 60 affixed to it an arm C². The latter at the outer extremity is provided with a weight C³. The weight C³ serves to rock the shaft, so that it will swing the belt-shifter C in a direction to shift the belt onto the loose pulley. There 65 is affixed to the rock-shaft C' a handle or arm C⁴, whereby the shaft may be rocked and the belt-shifter swung so as to shift the belt onto the fixed pulley b' to effect the rotation of the shaft B. After the belt-shifter has been 70 manipulated to shift the belt onto the fixed pulley, it will be maintained in that position automatically by a mechanism devised for this purpose. We will defer a description of this mechanism for the present, as it will conduce 75 to clearness to first describe some other parts.

The shaft B has affixed to it a balance-wheel B', which has the additional function of a hand-wheel, which may be grasped by the operator to adjust the shaft. At the forward end the shaft B is provided with a chuck D, which may be made of any approved type adapted to secure to the shaft a block E for sustaining a hat. In addition to the ordinary chuck we provide a positive lock between 80 the block and the shaft B. This lock consists of an arm D' bolted to the shaft and entering a hole in the rear of the block E. This insures the proper centering of the block upon the shaft.

The block E is intended to sustain a hat. While the hat is upon the block it will rotate with the block and the shaft B. During this rotation it will be subjected to the action of the pouncing-pads, of which we have shown 95 two G H. These pads may be of any desirable construction—as, for instance, they may be made of wooden blocks having attached to them pads of hair faced with sand-paper. These pads have a reciprocating motion. This 100

- motion, in conjunction with the rotary motion of the hat, enables the pads to operate upon all portions of the crown of the hat from the center of the tip right up to the brim.
- 5 The pad G has a shank g of tubular construction. In it is fitted a block g' , which conforms to the shank as a piston conforms to a cylinder, so that the one is incapable of any movement except a longitudinal movement relatively to the other. The tubular shank has in it two opposite longitudinal slots g^2 . Through these slots g^2 and through the block g' passes a cylindric extension g^3 of a lever g^4 . A cross-pin passing through 15 the extremity of the cylindric extension beyond the tubular shank of the pad secures the shank to the lever g^4 . Obviously the pad may swing relatively to the lever g^4 . This we have illustrated by dotted lines in Fig. 9.
- 20 In the tubular shank of the pad, between the body of the pad and the block g' , is a spiral spring g^5 , which serves to force the pad against the hat. The lever g^4 is fulcrumed between its ends by the pin g^6 to a block g^6 . The lever swings upon its fulcrum to adapt the pad to its work. A spring g^7 is attached to the outer end of the lever for the purpose of forcing the inner end downwardly toward the hat. At the upper end the spring is connected to a hook g^8 , having a screw-shank. A nut combined with the screw-shank serves to adjust the hook to vary the tension of the spring. This nut bears upon a bracket g^9 , secured to the block g^6 . The block g^6 is secured to an arm g^{10} , which is made in the form of a cylindric shaft, although it differs from a shaft in that it has no rotary movement. This arm g^{10} is supported by a reciprocating slider I.
- 30 The pad H has a tubular shank h like the tubular shank g of the pad G. This tubular shank is slotted longitudinally like the tubular shank g . A pin h^1 passes through the slots and through a block resembling the block g' , arranged within the shank h . This pin h^1 is at one end affixed to a bar h^2 . A cross-pin may be passed through the other end to retain the tubular shank upon the pin h^1 . The pad H can swing upon the bar h^2 , 45 and a spring arranged within this tubular shank and combined therewith and with the block in the shank in the same manner that the spring g^8 is combined with the pad G and its block serves to force the pad H against the hat. The bar h^2 is supported by two arms h^3 h^4 . The arm h^3 is rigidly secured to a sleeve h^5 , which is supported upon the arm g^{11} and is free to rotate or oscillate around the latter. A spring h^6 , coiled around the arm g^{11} , bears upon the outer portion of the arm h^5 and serves to press it toward the hat. This spring is shown as having the end portions coiled around the arm g^{11} and the middle portion bent into U form or V form, to straddle the arm h^5 . The extremities of the spring are of course secured to the arm g^{11} . The arm h^6 is pivotally connected at the upper end by a pin h^7 to the arm h^5 . It has at about the middle of its length a longitudinal slot h^8 . Through this passes a thumb-screw h^9 to h^{10} . This screw h^{10} also passes through the bar h^4 at one end and at the other has a nut. By means of this screw and nut the bar h^4 may be clamped in different positions to the arm h^6 . The upper end of the bar h^4 extends through a slot in the arm h^5 . It is secured within this slot by a screw h^{11} , having a head on one end and a nut on the other. There are a number of holes in the arm h^5 , through which the screw h^{11} may be passed to secure the bar h^4 to this arm at different points in the length of the latter. There are also a number of holes in the bar h^4 to enable the screws h^{10} h^{11} to be passed through it at different points in its length. The connection of the bar h^4 to the arm g^{11} by means of the arms h^5 and h^6 enables the pad H to be adjusted and held in different positions for operation upon the hat.
- 50 We have already explained that the arm g^{11} is secured to a slider I. As this slider reciprocates, the pads travel over the hat, and in order to do this they swing at different angles, being always free to yield, and yet held in contact with the hat by the action of the springs, which are combined with them.
- 55 The slider I is reciprocated by means of a wrist-pin i , affixed to a worm-wheel I'. This worm-wheel is supported upon a stud i' , erected upon a horizontally-extending part of the portion a' of the frame A'. Motion is imparted to this worm-wheel by a worm B² on the shaft B. A connecting-rod I² extends between the wrist-pin i and a pin i^2 on the slider.
- 60 The slider I is composed of two sections i^3 i^4 . The lower section i^3 travels along shears or ways i^4 on a bracket i^5 , erected on the bed-piece A. The section i^4 has a tongue-piece i^6 , which fits in a groove in the section i^3 . To the tongue-piece i^6 is secured a screw, which extends upwardly through the slot in the section i^3 . A nut i^7 engages with the screw and bears upon the top of the section i^3 . By means of this nut and the screw the tongue-piece i^6 of the section i^4 may be clamped to the section i^3 . The pin i^2 is secured to the section i^3 . The arm g^{11} is secured to the section i^4 . The movement imparted to the section i^3 by the wrist-pin i is of course always the same unless the connecting-rod is moved nearer to or farther from the center of worm-gear and the amount of reciprocating motion imparted to the section i^4 and the arm g^{11} , and the appurtenances of the latter is also invariable unless changed, as mentioned above; but, owing to the fact that the section i^4 may be adjusted lengthwise of the section i^3 , the reciprocating motion of the section i^4 , the arm g^{11} , and the appurtenances of the latter may occur at a different point relatively to the block E.
- 65 We have already explained that the belt-shifter after having been shifted to move the

belt onto the fixed pulley will be maintained automatically in such position. We will now describe the mechanism for this purpose.

J designates a slider-bar. It slides horizontally in bearings j, which are secured to the frame A'. This bar has a lateral projection, here shown as made in the form of a screw-stud j', passing through a longitudinal slot j'', with which the bar is provided. The rock-shaft C', having the arm C of the belt-shifter affixed to it, has also affixed to it an arm C⁵, extending transversely to the arm C, and approximately in the direction of the length of the shaft B. When the belt-shifter is adjusted to move the belt onto the fixed pulley b', the slider-bar J is adjusted by hand, so as to bring its stud j' under that part of the arm C⁵ which is near the rock-shaft. The stud j' will then support the arm C⁵ and hold the belt-shifter in position to maintain the belt upon the fixed pulley. The belt-shifter cannot move while the stud j' remains under the arm C⁵. The slider-bar J is, however, during the operation of the machine moved longitudinally to carry its stud j' beyond the arm C⁵. When the stud j' has been moved beyond the arm C⁵, the weight C³ will oscillate the rock-shaft, and thereby swing the belt-shifter in such direction as to cause it to move the belt from the fixed pulley onto the loose pulley. The slider-bar is moved longitudinally by means of a pawl K, pivotally connected to the lower end of a lever K', which is fulcrumed between its ends to the frame A'. To the upper end of this lever is connected a spring K². This spring oscillates the lever in such direction as to cause the pawl to travel backwardly along a series of ratchet-teeth, with which the upper edge of the slider-bar J is provided. On the under side of the worm-wheel I' is a downward projection i¹⁰, having an outer curved or cam face. When the cam-face contacts with the upper end of the lever K', it oscillates the lever in such direction that the pawl K will move the slider-bar J a distance equal to the length of one of the ratchet-teeth on the top of the bar. The slider-bar J will therefore be moved the distance of ratchet-tooth at each rotation of the worm-wheel. By connecting the screw-stud j' with the slider-bar J in the manner described provision is afforded for adjusting the position of this stud relatively to that portion of the slider-bar which is provided with the ratchet-teeth. This adjustment affords provision for varying the time that the stud will support the arm C⁵, and hence the time that the belt-shifter will maintain the belt upon the fixed pulley. The machine may therefore be adapted to pouncing different kinds of hats for the different periods which may be requisite. The pin k, which connects the pawl K with the lever K', is rigidly affixed to the pawl, but passes loosely through the lever. The web of the frame A' is provided with a hole equal to the oscillation of the opposite part of the lever K'. Through this

hole the pin k passes. At the extremity of this pin it has affixed to it a handle k'. This handle is near to the handle C⁴, whereby the rock-shaft C' is oscillated. Hence the pawl may be disengaged from the ratchet-teeth of the slider-bar on the side of the machine at which the rock-shaft is operated.

What we claim as our invention, and desire to secure by Letters Patent, is—

1. In a hat-pouncing machine, the combination of a rotary hat-block, a reciprocating pad having a tubular shank, a spring in said shank, a block in said shank, and a support extending through longitudinal slots in the shank and through a hole in the block, substantially as specified.

2. In a hat-pouncing machine, the combination of a rotary oval hat-block, a reciprocating slider consisting of two sections operated from the main shaft, a pad reciprocated in substantially one plane by the slider and connected thereto so that it may be adjusted longitudinally of the slider, substantially as specified.

3. In a hat-pouncing machine, the combination of a rotary hat-block, a reciprocating slider made in two sections and operated from a worm on the main shaft, and a pad connected to one of the sections and adjustable with said section relatively to the other, substantially as specified.

4. In a hat-pouncing machine, the combination of a rotary hat-block, a pad, a lever h⁴, supporting said pad, arms h⁵ h⁶, supporting the lever h⁴, and an oscillating sleeve to which the arm h⁵ is rigidly attached, substantially as specified.

5. In a hat-pouncing machine, the combination of a main shaft, a rotary hat-block having its axis parallel with that of the main shaft, a worm rotated by the main shaft, a worm-wheel engaging with the worm, a slider traveling on ways attached to the frame and reciprocated through the worm-wheel in the direction of the axis of the hat-block, and a pad carried by the slider and reciprocated by it over the hat-block, substantially as specified.

6. In a hat-pouncing machine, the combination of a rotary hat-block, a driving-shaft, a reciprocating pad, a belt-shifter, a holder for maintaining the belt-shifter in position to keep the belt on the fixed pulley of the driving-shaft, and a movable stop or support which ultimately will allow the reversal of the belt-shifter, substantially as specified.

7. In a hat-pouncing machine, the combination of a rotary hat-block, a driving-shaft, a reciprocating pad, a belt-shifter, a holder for maintaining the belt-shifter in position to keep the belt on the fixed pulley of the driving-shaft, and a stop or support movable with and adjustable on the holder, which ultimately will allow the reversal of the belt-shifter, substantially as specified.

8. In a hat-pouncing machine, the combination of a rotary hat-block, a reciprocating pad, a crank reciprocating the pad, a driving-shaft

effecting the revolution of the crank, fast and loose pulleys on the driving-shaft, a belt-shifter, a weight for moving the belt-shifter so as to cause it to shift the belt upon the loose pulley, and a movable support or stop for preventing the movement of the belt-shifter by the weight until the proper time, substantially as specified.

9. In a hat-pouncing machine, the combination of a rotary hat-block, a reciprocating pad, a crank reciprocating the pad, a driving-shaft effecting the revolution of the crank, fast and loose pulleys on the driving-shaft, a belt-shifter, a weight for moving the belt-shifter so as to cause it to shift the belt upon the loose pulley, and an adjustable and movable stop or support for preventing the movement of the belt-shifter by the weight until the proper time, substantially as specified.
10. In a hat-pouncing machine, the combination of a rotary hat-block, a reciprocating pad, a crank reciprocating the pad, a driving-

shaft imparting motion to the crank, fast and loose pulleys on the driving-shaft, a belt-shifter, a weight for moving the belt-shifter over the loose pulley, a support, as j' , a slider-bar, as J, a lever, as K', and a cam for operating the lever, substantially as specified.

11. In a hat-pouncing machine, the combination of a rotary hat-block, a reciprocating pad, a crank reciprocating the pad, a driving-shaft imparting motion to the crank, fast and loose pulleys on the driving-shaft, a belt-shifter, a weight for moving the belt-shifter over the loose pulley, a support, as j' , a slider-bar, as J, with which said support is adjustably connected, a lever, as K', and a cam for operating the lever, substantially as specified.
